[57] CLAIM

The ornamental design for decoration for roof edges, as shown and described.

DESCRIPTION

FIG. 1 is a fragmentary front elevational view of a decoration for roof edges showing my new design, the rear being a mirror image thereof the pattern being repetitive as shown in FIG. 1 of the drawing; FIG. 2 is a top plan view thereof; and, FIG. 3 is a bottom plan view thereof.

FIG. 1

FIG. 2

FIG. 3
